UNITED STATES PATENT OFFICE.

EDWARD ELLSWORTH MENGES, OF NEW HAVEN, CONNECTICUT, ASSIGNOR
TO THE SEAMLESS RUBBER CO., OF NEW HAVEN, CONNECTICUT, A COR-PORATION.

DESIGN FOR A WATER-BAG.

SPECIFICATION forming part of Design No. 36,397, dated June 30, 1903.

Application filed March 23, 1903. Serial No. 149,210. Term of patent 14 years.

To all whom it may concern:

Be it known that I, EDWARD ELLSWORTH MENGES, of New Haven, in the county of New Haven and State of Connecticut, have invented and produced a new, original, and ornamental Design for Water-Bags; and I do hereby declare the following accompanying drawing to be a full, clear, and exact illustration of the same, and which said drawing constitutes part of this specification, and represents a face view of a water-bag embodying my design.

I claim—

The ornamental design for a water-bag as shown.

In testimony whereof I have signed this specification in the presence of two subscribing witnesses.

EDWARD ELLSWORTH MENGES.
